UNITED STATES PATENT OFFICE.

MIFFLIN L. ASHBAUGH, OF ANDERSON, INDIANA.

ELECTRIC ACCUMULATOR.

1,096,587.

Specification of Letters Patent. Patented May 12, 1914.

Application filed April 12, 1913. Serial No. 760,616.

To all whom it may concern:

Be it known that I, MIFFLIN L. ASHBAUGH, a citizen of the United States, residing at Anderson, in the county of Madison 5 and State of Indiana, have invented certain new and useful Improvements in Electric Accumulators, of which the following is a specification.

My invention relates to improvements in 10 electric accumulators or so called storage batteries.

One of the objects of my invention is to provide a simple, efficient, and effective structure or active element of a battery cell.

Another object of my invention is to provide a battery element divisible into a plurality of parts, one superposed upon the other and all joined to a common conductor by means adapted and arranged to permit 20 relative movement of said parts during the time when the element, as a whole, is undergoing expansion and contraction, as when the battery, within which the said element is contained, is being charged and discharged.

Furthermore to compensate for increased 25 size of said parts as when the element "grows" under protracted use.

Still another object of my invention is to provide means in the containing case to 30 space the elements sufficiently apart to prevent contact and to permit free circulation of the electro-lyte to all of the active surfaces or parts of the respective elements.

Other and further objects of my invention 35 will become readily apparent to persons skilled in the art from a consideration of the following description when taken in conjunction with the drawings, wherein—

Figure 1 is a longitudinal sectional view, 40 taken on line 1—1 of Fig. 2; Fig. 2 is a plan view of my improved cell; Fig. 3 is a plan view of a grid composing part of one of the elements; Fig. 4 is a side view of the same; Fig. 5 is an enlarged cross sectional 45 view of two sections of an element, one superposed upon the other, taken on line 5—5 of Fig. 3; and Fig. 6 is a broken-away enlarged isometric view of one of the grids before being filled.

In all the views the same reference characters are employed to indicate similar 50 parts.

Each of the elements of my improved battery consists of a plurality of longitudinally 55 disposed vertically divided sections or grids 10, one superposed upon the other and spaced

apart by means of protuberances 11 placed at intervals along one upper or lower surface of the grids to provide space between the respective grids, as shown in Fig. 5, for 60 circulation of the electro-lyte. The specific form of the grid for the purpose of retaining the active material 12 is not of special importance in my present invention. In the particular exemplification I have shown a 65 cross sectional view of a grid each edge of which represents the letter E, as at 13, and 14, with a central double E placed back to back. The central rib 16 is perforated, as at 17, through which to key the active material and the overhanging ribs 18 serve furthermore as means for keying the active material and for affording mechanical surfaces for contact with the protuberances 11. The central rib 16 of the grids is notched at 70 the ends, as at 19, to provide recesses to receive the vertical ribs 20 projecting from the sides of the containing casing 21. The containing casing 21 is also provided with supports 22 on its bottom to support the elements as a whole and to provide pans to receive any conducting material that may, 80 from time to time, fall from the grids. Each of the grids 10 is provided on its end with a projection 23 which is, to a more or less 85 extent, flexible, that will permit the vertical displacement of the grids to some extent without disturbing its connection with the other grids with which it is associated. Each of the ends 23 is provided with a hole 90 24 that registers with holes in other grids that compose a given element. After the grids have been filled with active material 12, as shown in Fig. 5, they are placed one upon the other, as shown in Fig. 1, until a 95 sufficient number have been so assembled to provide an element of the proper vertical dimension. The tongues 23 and the perforations 24 therein are placed in the same vertical plane so that a wire or copper conductor 25, to afford better electrical conductivity for the conducting post 26, is placed in the vertically alining perforations 24 100 of the tongues 23. To prevent corrosion this wire is entirely inclosed in the metal 105 composing the post 26. When the parts are assembled in the manner described, the post 26 is molded around the ends or the tongues 23, of the assembled grids, and in molding the post 26, a notch 27, similarly 110 to the notch 19, is made in the end of the post for engagement with the ribs 20 of

the containing casing 21. In Fig. 1 the rib 20 of the casing 21 is shown within the notch 27.

In Fig. 2 I have shown the positive terminal 29 connected to two positive plates, or negative elements, 28, and the negative terminal 30 connected to three negative plates, or positive elements, 31, in the usual manner, as by burning, soldering, or otherwise. The terminals 29 and 30, respectively, are connected to the posts 26 of the respective elements as by burning, and the elements thus joined may be connected into battery arrangement by means of conductors engaging the reduced portions 34 (+) plus and 34 (-) minus of the cell terminals.

It will be observed that practically the entire surface of the active material comprising my grids is so disposed as to be subject to the action of the electro-lyte and free circulation thereof is permitted between the confronting surfaces of the sections, and furthermore that the means for spacing the respective elements apart and holding them in spaced relation does not shut off a particle of the confronting active surface of the respective grids. It will be furthermore observed that the flexible tongues 23 permit relative vertical movement of the sections composing the grids without danger of rupturing the contacting ends as these tongues are flexible and the joints made thereby are not rigid, as is usual in constructions of this general character.

By doing away with the perforated intervening separating plates, usually used in structures of this general character, the entire active surfaces of the grids are exposed and free for contact by the electro-lyte, and the internal resistance of the cell is thereby greatly decreased and coextensively increasing the general efficiency of the operation of the structure. In the operation of a cell of this character, there is very little, if any, lateral expansion of the elements due to causes to which reference has heretofore been made and in the structure which I have heretofore described, wherein longitudinally extending parallel sections are joined at one

end, the expansion will take place in a vertical direction and the joining ends, being flexible, permits the expansion and contraction of the respective sections without danger of permanent displacement of the parts.

While I have herein described a single embodiment of my invention for the purpose of clear disclosure, it is evident that changes may be made within the scope of the appended claims without departing therefrom.

What I claim is:

1. A battery element, comprising a plurality of vertically disposed, spaced-apart sections free to move with respect to one another, each section provided with a flexible tongue at one end by which they are united to a common conductor, projections extending from one side of each section to space apart an adjacent section and provide a gliding contact therewith, and a common conductor uniting said sections into a single element.

2. A battery element, comprising a plurality of vertically disposed, spaced-apart sections, each section provided with a notch or recess in its free end, and having a flexible tongue at the other end by which said sections are united to a common conductor; a common conductor for uniting said sections into a single element and having a vertically extending recess and a containing casing having vertically inwardly extending ribs to space apart said elements.

3. A battery element, comprising a plurality of vertically disposed, spaced-apart sections, each section provided with notches or recesses in its ends, and having a flexible tongue by which said sections are united to a common conductor, a common conductor for uniting said sections into a single element and a containing casing having vertically, inwardly extending ribs to space apart said elements.

In testimony whereof I hereunto set my hand in the presence of two witnesses.

MIFFLIN L. ASHBAUGH.

In the presence of—

FREDERICK VAN NUYS,
REN. A. HOFFMANN.
